poration of Michigan

Application November 15, 1945, Serial No. 628,905

5 Claims. (Cl. 230—20).

1

This invention relates to fluid pressure energy translating devices.

The invention is more particularly concerned with a fluid pressure energy translating device of variable displacement, and particularly adapted for use as a gas compressor.

It is an object of the present invention to provide a compressor particularly adapted for refrigeration and which has a variable volumetric displacement.

It is also an object to provide a compressor of this type in which the clearance volume is kept at a minimum and which furthermore is maintained at that minimum independently of changes in volumetric displacement of the compressor.

It is also an object to provide a compressor of this type which may be constructed from elements many of which are similar to those currently in successful use as fluid pumps and motors in the hydraulic power transmission field, and particularly those of the type utilizing a rotating cylinder barrel with axial pistons which are driven from a driving flange rotatable on an axis inclined to the axis of rotation of the cylinder barrel.

A further object of the invention is to provide in a compressor of this class an improved lubricating system which will insure adequate pressure lubrication to all moving parts of the mechanism and which preferably does not require the use of a separate lubricating pump.

Another object is to provide in a compressor of this class an improved shaft sealing means wherein a body of lubricating fluid is maintained adjacent the shaft at the point where it extends through the housing of the compressor which lubricating fluid is sealed both from the outside of the housing and from the inside space which contains refrigerant gas.

Further objects and advantages of the present invention will be apparent from the following description, reference being had to the accompanying drawings wherein a preferred form of the present invention is clearly shown.

In the drawings:

Figure 1 is a longitudinal sectional view of a variable displacement compressor embodying a preferred form of the present invention.

Figure 2 is an end view, partly in section, of the compressor shown in Figure 1.

Figure 3 is an end view of the yoke of the compressor, partly in section.

Figure 4 is the side view of the yoke shown in Figure 2.

2

Figure 5 is the top view of the yoke shown in Figure 2.

Figure 6 is the diagrammatic view showing a typical refrigerator circuit embodying the compressor of Figure 1.

Figure 7 is a fragmentary sectional view of a trunnion construction forming part of the compressor structure.

Referring now to Figure 1, there is illustrated 10 a housing 10 having a cover 12 and provided with a shaft receiving opening 14. A drive shaft 16 extends thru the opening 14 and is mounted on ball bearings 18 and 20. Suitable shaft seals are provided at 22 and 24 to form a sealed compartment 25 between them and in which the bearing 20 is mounted. The shaft 16 is provided with a driving flange 26 carrying a plurality, preferably an odd number, of ball sockets 28 to which ball ended connecting rods 30 are articulated. Each connecting rod 30 carries at its opposite ball end a piston 32.

Pivotedly mounted in the case 10 is a swinging yoke member 34 having two arms 36 which are pivoted to the housing on either side of the shaft opening 14 by means of trunnions 37 (Figures 4 and 7). The center of the trunnions 37 and the axis about which the yoke 34 tilts is tangent to the circle on which the centers of the sockets 28 are disposed. The yoke 34 is provided with a central transverse block section 38 which connects the two arms 36 and forms the mounting for a flat disc valve plate 40. The valve plate 40 is provided with flat annular sealing surfaces 42 and 44 on its left and right faces, the surface 44 being of slightly greater area than the surface 42. Abutting against the surface 44 is a cylinder barrel 46, having a plurality of cylinders 48 therein in which the pistons 32 are slidably mounted. The cylinder bores 48 extend straight through to the cylinder barrel from end to end so that the heads of pistons 32 may approach very closely to the valve plate surface 44.

The cylinder barrel 46 is pivotally mounted on a ball bearing 50 carried upon a cylinder mounting pin 52. The latter extends through a central hole of valve plate 40 with adequate clearance and also through a hole 54 in the block 38 provided with a seal 56. At its left hand end 50, the pin 52 carries a piston 58 also provided with a seal 60 and slidable in an enlarged bore 62 formed in the block 38. A light spring 64 urges the piston 58, pin 52, bearing 50 and cylinder barrel 46 into contact with the valve plate 40.

The cylinder barrel 46 is connected to rotate

in unison with shaft 16 by means of a Cardan shaft 66 having universal joints 68 and 70 at its opposite ends. The ends of the shaft 66 are spherical and abut against spherical sockets 72 and 74 which are mounted in bores 76 and 78, respectively, in the cylinder barrel 46 and shaft 16. The spherical abutment 74 is slidable in the bore 78 and is urged to the left by a spring 80, while the abutment 72 rests against a shoulder 82 in the cylinder barrel 46.

The yoke 34 is provided with an extended arm 84 which is pivotally connected by means of a link 86 with a rod 88 of a piston 90. The latter is slidably mounted in a cylinder 92 formed in the housing 10 and provided with an end cover 94.

Referring now to Figures 2 through 4, the valve plate 40 is provided with arcuate inlet and outlet ports 100 and 102 which extend through the valve plate from side to side. The ports 100 and 102 extend into the block 38 of yoke 34, the inlet port 100 extending through to the exterior of block 38. The discharge port 102 intersects a large bore 106 forming an oil separator and does not extend beyond the bore to the exterior of the block 38. The bore 106 is provided with concentric sleeves 110 and 112 to facilitate the separation of oil from refrigerant being delivered from the discharge port 102. The sleeve 112 provides an uptake pipe leading to a discharge connection 114 formed in a stationary pintle 116 mounted on the block 38. The pintle 116 forms a pivotal support for one element 118 of a combined telescoping delivery pipe and thrust reaction device. The other member 120 of the device (see Figure 2) is pivotally mounted to the housing 10 by a similar pintle 122 which forms the external delivery port for the compressor.

From the bottom of oil separator chamber 106, a passage 124 leads to the bore 62 in which the piston 58 is slidable. The pin 52 is provided with an internal passage 126 leading from the cylinder 62 to the right-hand end of pin 52 and the chamber 128 formed at the center of cylinder barrel 46. From the chamber 128 a plurality of short radial passages 130 lead to each of the cylinder bores 48. Each piston 32 is provided with a reduced diameter portion 132 of sufficient length to maintain contact with the passages 130 in all positions of the piston 32. Each piston 32 is provided with a passage 134 leading from the groove 132 to the socket portion of the piston. The connecting rods 30 are provided with central passages 136 extending from end to end and connecting their respective ball sockets. Also leading from the chamber 128 is a passage 138 leading through the abutment 72 to the spherical end surface of Cardan shaft 66. The latter is provided with a central longitudinal passage 140 extending from end to end and registering with a central passage 142 in the abutment 74. The shaft 16 is provided with a radial passage 144 extending from the right-hand end of bore 78 to the chamber 25 between seals 22 and 24. A small spring loaded ball valve 146 is provided opening out of the chamber between the seals and maintaining a predetermined pressure therein. The exit from the valve 146 opens into the housing 10.

The compressor displacement is controlled by piston 90, and, for simplicity, this may be made responsive directly to the suction pressure by connecting the left end of cylinder 92, in Figure 1, to atmosphere and connecting the right end thereof to the compressor casing by the provision of a passage 152 in the rod 88. In this case a large spring 154 is used to bias the yoke down-

wardly in Figure 1. Preferably, however, the piston 90 is operated by oil under pressure controlled by a valve responsive either to suction pressure or to temperature.

Such a valve is illustrated at the lower right-hand portion of Figures 1 and 2 and designated 170. It may take the form of a conventional four-way reverse valve for directing pressure oil from chamber 25 delivered through passage 168, selectively either to the left end of cylinder 92 through passage 172 or to the right end through passage 174. The stem of valve 170 is operated by a bellows 176 at its right-hand end, sealed to the wall of housing 10 which is thus responsive to suction pressure. A spring 178 normally biases the valve stem to the right. Provision for adjustment of spring 178 is made by means of the threaded stem of valve 170 which may be adjusted in and out relative to the end wall of the bellows 176. A lock nut 180 seals the threaded stem when tightened in place.

Referring now to Figure 6, there is shown diagrammatically a refrigerating circuit incorporating the compressor. The refrigerant feed line 156 runs from pintle 122 through a condenser 158, receiver 160, and expansion valve 162. The evaporator 164 is connected to the expansion valve and its outlet connects by suction line 166 to the housing 10.

In operation with shaft 16 being driven and with the system filled with refrigerant and with a quantity of oil partially filling the housing 10, with the parts in position shown in Figure 1, the displacement of the compressor is zero, and the shaft 16 and the cylinder barrel 46 are rotated without causing the pistons 32 to partake of any reciprocatory movement in the cylinders 48. In response to a demand for refrigeration, the control valve 170 will shift to admit oil to the right end of cylinder 92 exhausting oil from the left end and forcing piston 90 to the left to swing the yoke 34 counter-clockwise on a trunnion 37.

It will be understood that in the preferred construction using valve 170 that the spring 154 is omitted and the passage 152 is blocked. This inclines the axis of cylinder barrel 46 with respect to the axis of shaft 16 causing pistons 32 to partake of an in and out movement as they revolve about the cylinder barrel axis. Thus, as each piston passes the inlet port 100 it will be withdrawing away from the valve plate 40, thus drawing in a mixture of refrigerant and oil into its corresponding cylinder. As the piston passes across top dead center of Figure 1, the end of the cylinder 48 cuts off from inlet port 100 and opens up to discharge port 102, and while in contact with the same, the piston will move toward the valve plate discharging the contents of the cylinder into discharge port 102.

The mixed oil and refrigerant are separated in the bore 106, the gaseous refrigerant passing through the uptake pipe 112 passage 114, pintle 116 and through the telescoping delivery connection to the compressor discharge port 122. The volumetric displacement of the compressor per revolution will be determined by the angle of inclination of the cylinder barrel axis to the shaft axis and can be varied to suit requirements by operation of the control valve 170 and control piston 90. Thus, the compressor will deliver refrigerant at any rate required to meet both varying refrigerant demands and also to compensate for variations in speed at which the shaft 16 is driven. The oil which is separated in the oil separating chamber 106 is under refrigerant dis-

charge pressure and is conducted through the passage 124 to the chamber 62 where it acts upon the right face of piston 58; the area of piston 58 is so chosen with respect to the area of the valve plate surface 44 as to almost entirely compensate for the pressure acting on the end surface of cylinder barrel 46 tending to separate it from the valve plate 40. Preferably, the area of piston 58 may be so chosen as to overcompensate and thus create a slight increased hold down force as the discharge pressure rises.

From the bore 62, oil is delivered thru the passage 126 to the chamber 128 where it is available for distribution under pressure through the radial passages 130 to the ball and socket joints of connecting rods 30, escaping finally through the clearance between the ball and socket 28. Another portion of the oil delivered to chamber 128 passes through the passages 138, 140 and 142 lubricating the universal joint pivots and finding its way ultimately through the passage 144 to the chamber 25. It will be noted that the area of the spherical retainers 72 and 74 are preferably equal, thus eliminating any tendency for oil pressure to shift the Cardan shaft endwise, its position being maintained by the spring 80 and the shoulder 82. The oil in the chamber 25 lubricates bearing 28 and finally passes to the interior of the housing 10 through the relief valve 146. The latter preferably has a setting slightly below the minimum discharge pressure for which the compressor is designed so that there will be a continual flow through the path as previously described. The oil, finding its way back to the interior of housing 10, will again be entrained in the refrigerant taken in through intake passage 104 and thus start upon another cycle of oil circulation.

It will be noted that the telescoping delivery connection has a larger area than necessary for delivery purposes and this is provided for the purpose of balancing the fluid pressure forces acting upon the yoke 34. It will be seen that the thrust of the fluid in those cylinders which are in contact with the discharge port 102 are acting on the yoke 34 at a distance from the trunnion 31, thereby creating a couple tending to swing the yoke 34 counterclockwise. The area of the telescoping discharge connection is preferably so chosen with regard to its lever arm on the yoke as to exactly counter balance the piston thrust acting on the yoke, thus leaving the yoke free to take up any position dictated by the control piston 90.

It will also be noted that the construction described provides for a minimum clearance volume and that this clearance volume is independent of the position of yoke 34. By pivoting the yoke 34 on an axis tangent to the circle on which the connecting rod socket centers are located on the driving flange, it will be seen that each piston, as it passes the bottom dead center position in Figure 1, will be closely adjacent to the valve plate regardless of the position of yoke 34. That is because the center of the socket 28 at that moment is coincident with the pivotal axis of yoke 34 and thus swinging of the yoke cannot cause any inward or outward movement of a piston while it is in this position.

The present invention thus provides a variable displacement compressor eminently suited for refrigeration service, either for constant speed drive, as from an electric motor prime mover, or for variable speed drive, directly from a railway

car axle or from a motor vehicle engine, for example.

While the form of embodiment of the invention as herein disclosed constitutes a preferred form, it is to be understood that other forms might be adopted, all coming within the scope of the claims which follow.

What is claimed is as follows:

1. A variable stroke compressor comprising in combination, a housing, a drive shaft journalled in the housing and having a plurality of sockets arranged in a circle about one side thereof, a yoke pivotally mounted on the housing to swing about an axis tangent to the socket circle and including a distributing valve surface having an inlet port and an outlet port, a cylinder barrel rotatably mounted on the yoke and having a plurality of axial cylinders therein, distributing ports in the cylinder barrel cooperating with the ports in the distributing valve surface, universal joint mechanism connected between the drive shaft and the cylinder barrel, a plurality of pistons slidably mounted in the cylinders, connecting rods articulated to the pistons and to the sockets on the driving flange, and means for substantially counteracting the net thrust on the yoke produced by fluid pressure within the cylinders, said means including a telescoping piston and cylinder assembly connected between the yoke and the housing and forming a fluid delivery conduit between the swingable yoke and a fixed point on the housing.

2. A variable stroke compressor comprising in combination, a housing, a drive shaft journalled in the housing and having a plurality of sockets arranged in a circle about one side thereof, a yoke pivotally mounted on the housing to swing about an axis tangent to the socket circle and including a distributing valve surface having an inlet port and an outlet port, a cylinder barrel rotatably mounted on the yoke and having a plurality of axial cylinders therein, distributing ports in the cylinder barrel cooperating with the ports in the distributing valve surface, universal joint mechanism connected between the drive shaft and the cylinder barrel, a plurality of pistons slidably mounted in the cylinders, connecting rods articulated to the pistons and to the sockets on the driving flange, an inlet connection leading to the interior of the housing, a delivery connection from the outlet port in the yoke to the exterior of the housing, an oil separator in communication with said delivery connection and having an oil delivery passage subject to outlet pressure, and passages leading from the oil delivery passage to said pistons and articulated connecting rods.

3. A variable stroke compressor comprising in combination, a housing, a drive shaft journalled in the housing and having a plurality of sockets arranged in a circle about one side thereof, a yoke pivotally mounted on the housing to swing about an axis tangent to the socket circle and including a distributing valve surface having an inlet port and an outlet port, a cylinder barrel rotatably mounted on the yoke and having a plurality of axial cylinders therein, distributing ports in the cylinder barrel cooperating with the ports in the distributing valve surface, universal joint mechanism connected between the drive shaft and the cylinder barrel, a plurality of pistons slidably mounted in the cylinders, connecting rods articulated to the pistons and to the sockets on the driving flange, an inlet connection leading to the interior of the housing, a delivery connection from the outlet port in the yoke to the exterior

of the housing, an oil separator in communication with said delivery connection and having an oil delivery passage subject to outlet pressure, and passages leading from the oil delivery passage to the universal joint mechanism.

4. A variable stroke compressor comprising in combination, a housing, a drive shaft journalled in the housing and having a plurality of sockets arranged in a circle about one side thereof, a yoke pivotally mounted on the housing to swing about an axis tangent to the socket circle and including a distributing valve surface having an inlet port and an outlet port, a cylinder barrel rotatably mounted on the yoke and having a plurality of axial cylinders therein, distributing ports in the cylinder barrel cooperating with the ports in the distributing valve surface, universal joint mechanism connected between the drive shaft and the cylinder barrel, a plurality of pistons slidably mounted in the cylinders, connecting rods articulated to the pistons and to the sockets on the driving flange, said housing being subject to the suction pressure of the compressor, an oil pressure chamber surrounding the drive shaft, oil separating means associated with the outlet port, a passage connecting the oil separator to said oil pressure chamber, and a pair of shaft seals on either side of the oil pressure chamber, one sealing oil leakage from the oil chamber to the exterior of the housing and the other sealing oil leakage from the oil chamber to the interior of the housing.

5. A variable stroke compressor comprising in combination, a housing, a drive shaft journalled in the housing and having a plurality of sockets arranged in a circle about one side thereof, a yoke pivotally mounted on the housing to swing about an axis tangent to the socket circle and including a distributing valve surface having an inlet port and an outlet port, a cylinder barrel rotatably mounted on the yoke and having a plurality of axial cylinders therein, distributing ports in the

8

cylinder barrel cooperating with the ports in the distributing valve surface, universal joint mechanism connected between the drive shaft and the cylinder barrel, a plurality of pistons slidably mounted in the cylinders, connecting rods articulated to the pistons and to the sockets on the driving flange, said housing being subject to the suction pressure of the compressor, an oil pressure chamber surrounding the drive shaft, oil separating means associated with the outlet port, a passage connecting the oil separator to said oil pressure chamber, a pair of shaft seals on either side of the oil pressure chamber, one sealing oil leakage from the oil chamber to the exterior of the housing and the other sealing oil leakage from the oil chamber to the interior of the housing, and a relief valve opening from the oil chamber to the interior of the housing.
